CLAIM

(57) The ornamental design for an actuator nozzle for a diffusion device, as shown and described.

DESCRIPTION

FIG. 1 is an isometric view of a front, top, and left side of an ornamental design for an actuator nozzle for a diffusion device;

FIG. 2 is a right side elevational view of the actuator nozzle of FIG. 1;

FIG. 3 is a left side elevational view of the actuator nozzle of FIG. 1;

FIG. 4 is a bottom plan view of the actuator nozzle of FIG. 1; FIG. 5 is a front elevational view of the actuator nozzle of FIG. 1;

FIG. 6 is a rear elevational view of the actuator nozzle of FIG. 1; and,

FIG. 7 is a top plan view of the actuator nozzle of FIG. 1. The broken lines are for the purpose of illustrating environmental structure and form no part of the claimed design.
